2,009,307

STEAM TURBINE FOR NAVAL PROPULSION

Giuseppe Belluzzo, Rome, Italy

Application December 22, 1933, Serial No. 703,613
In Italy February 14, 1933

5 Claims. (Cl. 60—70)

When screw shafts are driven by means of turbines and geared reducers it is important to limit the space occupied in plan by the group by reducing the dimensions of the turbines within 5 possible limits. When on the contrary the question is of the same shaft driven by means of three or more turbines respectively of high, intermediate and low pressure then it is necessary to have in the first two turbines the same speed 10 and the same length.

Now when the cruising wheels besides those for full power are incorporated in the high pressure turbine, the problem can then not easily be solved, while it is simplified when the cruising 15 wheels are distributed between the two turbines of high and intermediate pressure.

The object of the present invention is to distribute the cruising wheels of the turbine between the high pressure turbine and the intermediate 20 pressure turbine in a construction in which action of certain of the turbine wheels may be cut out thereby increasing efficiency at varying speeds.

Figures 1 and 2 are diagrammatic sectional 25 views showing the assembled plant and different types of turbines that may be used therein.

The general arrangement will be best understood by reference to Figs. 1 and 2 in which the high pressure turbines are indicated by reference 30 letter M, the intermediate pressure turbines are indicated by reference letter N and the low pressure turbine is indicated by reference letter O.

The two turbines of high and intermediate pressure respectively control the pinions P_1 and 35 P_2 engaging the tooth wheel R mounted on the screw-bearing axle the low pressure turbine controlling pinion P_3 also engaging and controlling wheel R.

The high pressure turbine comprises two groups 40 of wheels A and B, the latter group and the group C of the intermediate pressure turbine consisting of the two groups C and D forming what has been termed the cruising wheels.

Casings about the high pressure turbines form 45 chambers 2, 3 and 4. Chamber 2 communicates with chambers 3 and 4 through valves V and W. Conduit T₂ leads from chamber 4 to 4₁ leading to group C of the intermediate turbine. Conduit T₁ leads from chamber 3 to the group D of the 50 intermediate pressure turbine.

Conduit T₃ leads from the discharge chamber 5 of group D of the intermediate pressure turbine to the low pressure turbine O.

The high pressure turbine is thus connected 55 with the intermediate pressure one by two pip-

ings of a different diameter; the one of a larger diameter is the main piping, uniting the capacity 3 of the two turbines and is run through by the steam for full power; the smaller piping uniting the two capacities 4 is on the contrary run through by the cruising speed steam.

When valves V and W are closed the group of turbines functions at the lowest speeds, the steam, when introduced in 1, after acting on group A of high pressure wheels runs in series 10 through the group of wheels B, is discharged in chamber 4, flows through the tube T₂, then acts on the intermediate pressure turbine N by flowing successively through the groups of wheels C and D of this turbine N and is then discharged 15 in chamber 5 from which through the tube T₃ reaches and actions the low pressure turbine O.

At full cruising speeds the valve W is open the valve V on the contrary is closed and then the steam flows through the group of wheels A jumps 20 over the group of wheels B of the high pressure turbine, because the valve V is closed, is discharged in chamber 4, which by means of tube T₂ leads the steam to the intermediate pressure turbine, from which the steam flows in series 25 through the groups C and D and is discharged in chamber 5, which by means of tube T₃ is in communication with the low pressure turbine.

At full speeds the valve W of the high pressure turbine M is closed and on the contrary the 30 valve V is open, the steam then after flowing through the group of wheels A of the high pressure turbine M is discharged from chamber 2 through the valve V into chamber 3 and from this chamber, through tube T₁ reaches the intermediate pressure turbine N₁ flowing only 35 through the group of wheels D being then discharged in 5 in order to flow by piping T₃ to the low pressure turbine.

By the arrangement disclosed it is possible to 40 employ the necessary cruising wheels to obtain the best efficiency, whatever may be the speed; and by conveniently distributing these wheels between the two turbines of high and intermediate pressure, the lengths of these turbines and consequently 45 their supports may be kept equal, together with packings and other accessories, the reserve of change or spare pieces being reduced.

Having now particularly described and ascertained the nature of my said invention and in 50 what manner the same is to be performed, I declare that what I claim is:

1. Driving apparatus for naval propulsion comprising a high pressure turbine composed of two 55 groups of wheels, the second group being cruising

wheels, an intermediate pressure turbine composed of two groups of wheels, the first group being cruising wheels, the cruising wheels being distributed between the two turbines of high and 5 intermediate pressure, conduits leading from the exhaust of the said first group of said high pressure turbine and branching, one branch surrounding the cruising wheels of said high pressure turbine and leading to the second group of said intermediate turbine and one branch leading to the 10 cruising wheels of said intermediate turbine and valves for each of said branches.

2. A driving apparatus for naval propulsion comprising a high pressure turbine composed of 15 two groups of wheels, the second group being cruising wheels, an intermediate pressure turbine composed of two groups of wheels, the first group being cruising wheels and one or two low pressure turbines, a conduit connecting the intermediate pressure turbine to the lower pressure turbine, the cruising wheels being distributed between the two turbines of high and intermediate pressure and conduits leading respectively from the exhaust of said first group of said high pressure 20 turbine to the second group of said intermediate pressure turbine and to the cruising wheels of said intermediate pressure turbine, the exhaust from said cruising wheels of said high pressure turbine opening into the said last named conduit 25 and valve in said conduits.

3. A driving apparatus for naval propulsion comprising a high pressure turbine composed of two groups of wheels, the second group being

cruising wheels, an intermediate pressure turbine composed of two groups of wheels, the first group being cruising wheels and the cruising wheels being distributed between the two turbines of high and intermediate pressure, and means for conducting the exhaust of the first cruising wheels to the inlet of the second cruising wheels. 5

4. A driving apparatus for naval propulsion comprising a high pressure turbine composed of two groups of wheels, the second group being 10 cruising wheels, an intermediate pressure turbine composed of two groups of wheels the first group being cruising wheels and the cruising wheels being distributed between the two turbines of high and intermediate pressure, means 15 for conducting the exhaust of the first cruising wheels to the inlet of the second cruising wheels and means for by-passing the first cruising wheels.

5. A driving apparatus for naval propulsion 20 comprising a high pressure turbine composed of two groups of wheels, the second group being cruising wheels, an intermediate pressure turbine composed of one group of wheels the first group being cruising wheels, and the cruising wheels being distributed between the two turbines of high and intermediate pressure, means 25 for conducting the exhaust of the first cruising wheels to the inlet of the second cruising wheels and means for by-passing both groups of cruising 30 wheels.

GIUSEPPE BELLUZZO.
